INVENTOR:

UNITED STATES PATENT OFFICE.

EBERHARD KOCH, OF NEW ORLEANS, LOUISIANA.

APPARATUS FOR DISTILLING WOOD.

SPECIFICATION forming part of Letters Patent No. 316,794, dated April 28, 1885.

Application filed July 18, 1884. (No model.)

To all whom it may concern:

Be it known that I, EBERHARD KOCH, of New Orleans, in the parish of Orleans and State of Louisiana, have invented a new and useful Improvement in Apparatus for Distilling Wood, which improvement is fully set forth in the following specification and accompanying drawings, in which—

Figure 1 is a longitudinal vertical central section of my improved steam-carbonizing apparatus, with a side view of the car and turn-table, and Fig. 2 is a front view of the same. The present invention relates to an improved apparatus for distilling wood, for the dry distillation of wood, and the charring of the same. In the device at present in use it is frequently necessary for the operator to enter the retorts, which require to be more or less cooled for the purpose, and great expense is incurred in the loss of heat and the injurious effects of continual expansion and contraction of the retort and masonry. I design to overcome these defects by means of a retort which is provided with a track extending from the outside, by means of which a car containing the wood to be charred may be run into the retort, after which it is sealed up. Beneath the retort is a furnace through which passes a coil-pipe extending into the retort, through which steam from the generator passes. The said super-heated steam passes through the retort containing the wood. The steam, after acting on the wood and being impregnated with the vapors rising from the wood, passes out through a pipe into a worm immersed in cold water, and is thus liquefied. This liquid may afterward be changed, distilled, and rectified into its component parts, all of which will now be fully set forth in detail.

In the accompanying drawings, A is a sheet-iron retort, of the proper size, provided externally with suitable masonry, B. The lower end of the retort is provided with a suitable furnace, C, having a suitable flue, D, extending rearwardly beneath the retort, and having a suitable outlet or chimney, E. A coil-pipe, F, having its forward end opening outwardly at the front of the furnace, extends inwardly through the furnace and the flue D, 50 thence upwardly at its rear end and opening

inwardly into the retort A. The forward end of this coil-pipe is designed to communicate with a suitable steam-generator, from which steam may be passed through the said coil into the retort A. This steam-generator, 55 however, is not shown in the drawings. The forward side of the retort is provided with a door, G, and also external enveloping masonry. The external masonry, B, is also provided with a door, H. A space is designed 60 to be provided between the retort and the external walls of the apparatus, so that the heat from the furnace may envelop the retort on all sides.

Upwardly from the retort A, and preferably at the forward side, I provide a pipe, I, of suitable size, curved laterally and passed down into and through a vessel of cold water in the form of a coil, J. The lower end of this coil is provided outwardly with a stop-cock, K, by means of which the distilled matter may be drawn off into a suitable reservoir. A suitable steam-gage, L, communicating inwardly with the retort, is placed in any suitable position over the apparatus, by means of 75 which the temperature of the retort may at all times be shown.

Immediately forward and opposite this apparatus I design to provide a second retort, in all respects similar to the first, for the especial purpose and to act as a cooling-reservoir for the carbonized wood removed from the retort, as otherwise the same, on coming in contact with the air, would ignite immediately. Between these apparatuses I design to furnish 85 a track by means of which a car, M, having a turn-table, N, thereon, may be run in between the apparatuses. This turn-table has rails thereon at a suitable distance apart, and designed to be at the same height from the 90 ground as the track O within the retort. This car and turn-table M are designed to receive thereon a car, P, of any suitable construction, and designed to receive the wood therein.

In operating this device, the cars are loaded 95 and run onto the turn-table, and the doors H and G being removed, are introduced into the retort. The said doors are then closed and made steam-tight by means of suitable packing between the doors and flange, and may 100

either be screwed down or secured by keys, as desired. Fire is then started within the furnace to heat the coil, after which steam is introduced through the coil from the generator. The steam, after passing into the retort, heats the wood therein, and, being impregnated with the vapors issuing from the wood, passes out through the pipe I, through the worm J, immersed in cold water, where it is liquefied. This liquid, on being drawn off through the cock K into a suitable reservoir, may pass through a system of distillation and rectification, as found necessary. When the operation of carbonizing is finished, the portable turn-table may be run up in front of the apparatus, after which the doors G and H open or are moved, which permits of the cars containing the carbonized wood being pushed out upon the said turn-table and removed. A second set of cars, already loaded, is now forthwith introduced into the retort, and the process repeated as before.

As will be noticed, in order that an equitable temperature may be obtained on all sides 25 of the retort, communication is had therewith to the furnace, and the fire from the furnace forced to pass over the front of the retort when closed, as well as at their other sides, before it is allowed to escape through the 30 chimney.

By using the steam-gage, the operator has the temperature at all times under control, which is of great importance, as the material to be used in distilling varies greatly in the 35 different degrees of heat required in their operation. This avoids the danger of damage to some carbonized material by overheating, which would be unavoidable without the use of said pyrometer. I also find that, by the use of

superheated steam, instead of an open fire, a 40 better quality and a greater quantity of products are obtained.

What I claim is—

1. The combination of a metallic retort having suitable external masonry, the forward 45 side having air-tight doors, the retort having steam-tight doors at the forward side, with a steam-generator and furnace adapted to heat the retort, with a superheater located in the said furnace to deliver superheated steam into 50 the retort, substantially as described.

2. The combination, with a furnace, as described, of a retort having flues at the front and rear ends, and a coil-pipe or superheater located in a horizontal flue, D, of said furnace 55 and over the fire-chamber, substantially as described.

3. The combination of the retort, provided with an air-tight door, a rail-track therein for a car-truck, a furnace having a flue, D, beneath the retort, a steam-superheating pipe-coil in said flue communicating with the interior of the retort, and a pipe leading from the latter to a condenser, substantially as described. 65

4. The combination of a retort having a coil-pipe or steam-superheater, F, connected therewith, the furnace, the steam-gage, the condensing apparatus, and the car provided with a turn-table and track, substantially as 70 and for the purposes herein set forth.

In testimony that I claim the foregoing I have hereunto set my hand, this 29th day of May, 1884, in the presence of witnesses.

EBERHARD KOCH.
